ATTORNEY

UNITED STATES PATENT OFFICE.

ANDREW M. HUNT, OF NEW YORK, N. Y., ASSIGNOR TO STANDARD STOKER COMPANY, INCORPORATED, A CORPORATION OF DELAWARE.

STOKER CONSTRUCTION.

Application filed January 27, 1925, Serial No. 5,025.

This invention relates to mechanical stokers and particularly to locomotive stokers wherein a screw conveyor is employed to carry the coal forward from the tender to the locomotive.

In conveyors of this type and particularly those wherein the coal is moved beyond the end of the screw-conveyor, upwardly through an unobstructed conduit, to a point above the fire and is there distributed over the fire by steam jets, if the conveyor screw at its forward end has only a single thread or flight, the delivery of the coal from the mouth of the conduit is intermittent rather than continuous. The coal moves upward during a portion of each revolution of the screw and remains stationary during the remainder of the revolution. Continuous delivery of coal to the fire box is desirable and the main object of the present invention is to provide means for effecting this result. For this purpose, I provide the conveyor screw at its forward or delivery end with a plurality of threads so positioned as to produce a continuous delivery of coal through the upwardly extending conduit.

Other objects and advantages of my invention will appear from the following description taken in connection with the accompanying drawing which shows one embodiment of my invention and, wherein a conveyor adapted to extend from the locomotive tender to the locomotive fire box is shown partly in elevation and partly in section.

The numeral 10 indicates the rear water leg of a conventional locomotive boiler which is positioned in front of the cab deck 12. 14 is a screw conveyor which is adapted to carry coal from the locomotive tender to a point in the fire box below the grate 16. The forward portion of the conveyor screw is formed of sections 17 and 18. Section 17 drives sections 18 through a universal joint 19 as is customary in locomotive conveyors of this type. Sections 17 and 18 are contained in housings or conduits 20 and 21 respectively and these housings are provided with universal joints as is customary. At the forward end of the housing 21 is an elbow 24 which supports an unobstructed conduit or core tube 25 slightly expanding which rises to the discharge mouth 26 which is surrounded by the protective grate 27. Located at the mouth 26 of the conduit 21 is a distributor head 28 which is formed with openings

29 adapted to form steam jets to blow the coal over the fire. The section 18 of the conveyor screw has at its forward end an additional thread 30 for the purpose of causing the coal to be delivered to the elbow 24 and upward through the conduit 25 in a continuous stream. While I have shown the screw conveyor as having a single thread with the additional thread 30 at its forward end only, it will be appreciated that the thread 30 may be continued through a greater portion of the screw. I find, however, that it is preferable to employ the additional thread at the forward end only and of a length of approximately $\frac{3}{4}$ of a turn of the thread. It is also obvious that, if desired, an additional number of threads may be employed at the forward end. Care should be taken, however, not to reduce the area of the passage so as to interfere with the movement of the coal.

I claim:

1. In a locomotive stoker, a forwardly extending conduit which terminates in an elbow, a conveyor screw in said conduit and an upwardly extending unobstructed conduit adapted to receive coal from said first named conduit and deliver the same to the fire box, the conveyor screw being formed at its delivering end with a plurality of threads delivering the material in a generally axial direction at their ends so as to cooperate with said elbow to give a substantially continuous upward pressure on the material and cause a continuous advance of coal through said upwardly extending conduit.

2. In a locomotive stoker, a forwardly extending conduit which terminates in an elbow, a conveyor screw in said conduit and an upwardly extending unobstructed conduit adapted to receive coal from said first named conduit and deliver the same to the fire box, the conveyor screw being formed at its delivering end for approximately an axial distance of three-quarters of a turn of the screw thread with a plurality of threads delivering the material in a generally axial direction at their ends so as to cause a continuous advance of coal through said upwardly extending conduit.

3. In a locomotive stoker, a forwardly extending conduit which terminates in an elbow, a conveyor screw in said conduit and an upwardly extending unobstructed conduit adapted to receive coal from said first

named conduit and deliver the same to the fire box, said conveyor screw being formed with a greater number of threads at its delivery end than the other portions delivering the material in a generally axial direction at their ends so as to cooperate with said elbow to give a substantially continuous upward pressure on the material and cause a continuous advance of coal through said upwardly extending conduit.

4. In a locomotive stoker, a forwardly extending conduit which terminates in an elbow, a conveyor screw in said conduit and an upwardly extending unobstructed conduit adapted to receive coal from said first named conduit and deliver the same to the fire box, said conveyor screw being formed with a double thread at its delivering end and a single thread at other portions so as to deliver the material in a generally axial di-

rection at the end of the double threads and cooperate with said elbow to give substantially continuous upward pressure on the material and cause a continuous advance of coal through said upwardly extending conduit. 25

5. In a locomotive stoker, a forwardly extending conduit which terminates in an elbow, a conveyor screw in said conduit and an upwardly extending unobstructed conduit adapted to receive coal from said first 30 named conduit and deliver the same to the fire box, said screw being formed with a double thread at its delivering end for an axial distance of approximately three-quarters of a turn of the thread and with a single thread at other portions, said double thread acting to deliver material in a generally axial direction at said elbow. 35

ANDREW M. HUNT.
